[57] CLAIM

The ornamental design for a cabinet for electronic processing equipment and the like, as shown and described.

DESCRIPTION

FIG. 1 is a top, front, side perspective view of a cabinet for electronic processing equipment and the like showing my new design;

FIG. 2 is a top plan view thereof;

FIG. 3 is a top, rear, side perspective view thereof, the side shown is opposite that shown in FIG. 1;

FIG. 4 is an enlarged side elevational view thereof, the front, rear, and opposite side being identical.

FIG. 1

FIG. 2

FIG. 3

FIG. 4
